UNITED STATES PATENT OFFICE.

CLARENCE G. WELSZ, OF PALMYRA, MISSOURI.

BASE FOR FENCE POSTS.

Application filed June 18, 1928. Serial No. 286,236.

The present invention relates to improvements in metallic building structures, and has reference more particularly to a metallic base for fence posts.

5 One of the important objects of the present invention is to provide a fence post base that can be readily and easily driven into the ground to provide a firm and positive support for the fence post.

10 A further object is to provide a fence post base which is simple in construction, inexpensive, strong and durable and further well adapted to the purpose for which it is designed.

15 In the accompanying drawings wherein like reference characters indicate corresponding parts throughout the same;

Figure 1 is a perspective view of one form of base or a fence post.

20 Figure 2 is a detail perspective view of the inverted U-shaped unit that provides a support for the lower end of the fence post for use in conjunction with the base shown in Figure 1, and

25 Figure 3 is a detail perspective view of another form of base.

In the drawing with reference more particularly to Figures 1 and 2, the numeral 1 designates generally the fence post base, the 30 same being formed from heavy galvanized sheet steel or other highly rust resisting metal. In constructing this base, a triangular shaped piece of material is bent along the lines 2-2 whereby to provide an intermediate back wall 3 and the parallel spaced side walls, 4, the vertical free edges of said side walls gradually tapering toward the lower end of the rear wall 3. The lower extremity of the rear wall 3 is pointed as indicated at 5 whereby the base may be readily and easily driven into the ground. For the purpose of anchoring the base in the ground, the lower end portions of the side walls 4 are cut to form the anchoring prongs 6 as clearly shown in Figure 1. These prongs are bent outwardly.

A salient part of the base 1 is the substantially inverted U-shaped unit 7 shown in Figure 2 that is also constructed of the same material as the base 1, and the side portion 8 is adapted to be rigidly secured to the rear wall 3 by any appropriate fastening means at a point below the top of the base and the crown portion 9 projects horizontally between the side walls 4 while the other or outer side 10 extends beyond the side edges of the side walls

and the lower free end of this side wall 10 is pointed to also enter the ground very easily. The pointed free end of the outer side 10 is designated by the reference character 11.

60 The inverted U-shaped unit 7 cooperates with the upper portion of the base 1 to provide a socket to receive the lower end of the fence post, shown in the dotted lines, and the lower end rests on the crown portion 9 of the inverted U-shaped member 7, while suitable openings 12 are formed in the side walls 4 adjacent the upper edge thereof to accommodate nails or other fastening means that may be driven into the sides of the fence post to 65 rigidly secure the same in the socket formed in the upper portion of the base.

70 In Figure 3 there is shown another form of a fence post base wherein the same comprises an angle iron unit 13, the vertical free edges of the sides gradually converging toward the lower end and terminating in a ground engaging point 14. The upper edge portions of the sides of the angle iron unit are formed with openings 15 to accommodate 75 suitable fastening means that may be driven into the adjacent sides of a fence post that has its lower end portion positioned in the upper portion of this angle iron unit 13.

75 It will thus be seen from the foregoing description, that I have provided a fence post base that can be readily and easily driven into the ground and will provide a rigid support for a fence post, and will not necessitate the fence post having to be driven into the ground, thus avoiding deterioration of the fence post, and rendering the same strong and durable.

80 While I have shown the preferred embodiment of my invention it is to be understood that minor changes in the size, shape and arrangement of parts may be resorted to without departing from the spirit of the invention, and the scope of the appended claim.

85 Having thus described the invention, what I claim is:

90 In a fence post base, a substantially channel shaped metallic unit, the side walls thereof having their outer edges gradually tapering toward the lower end of the unit, the lower end of the rear wall of the unit being pointed and adapted to be driven into the ground, the upper portion of the channel shaped unit providing a fence post receiving socket, the sides of the socket being formed 95 with fastening means receiving openings, and a substantially inverted U-shaped bracket 100

105

110

135

having one of its sides secured to the rear wall of the channel shaped unit, the crown portion of said inverted U-shaped bracket being adapted for engagement with the bottom of a fence post positioned in the socket, the other side of the U-shaped bracket projecting beyond the free edges of the sides of the channel shaped unit and extending downwardly, the

free end of the last mentioned side of the bracket being pointed and adapted to be driven into the ground, the lower portions of the sides of the channel shaped unit being formed with anchoring elements.

In testimony whereof I affix my signature.

CLARENCE G. WELSZ.
